UNITED STATES PATENT OFFICE

LOUIS DAVIDSON, OF NEW YORK, N. Y.

ARCH OR TRUSS SHOE

Application filed December 10, 1926. Serial No. 153,891.

The present invention relates to an arch or truss shoe especially adapted for use with long span arch constructions, and aims to provide certain improvements therein. More specifically, it constitutes an improvement on my earlier Patent No. 1,480,882, dated January 15, 1924, and has for its objects (1) to provide an arch or truss shoe of simple construction which may be cheaply fabricated; (2) one which will provide easy and rapid assembly of the arch in the field; (3) one which will provide a maximum amount of clearance between the floor and roof of a building, thus providing for a maximum amount of light and air, and (4) one which may be used for either permanent or temporary construction work with equal facility.

In the accompanying drawings I have illustrated several embodiments of my invention, wherein—

Figure 1 is a partial elevation of a long span arch construction embodying the arch or truss shoe of my invention;

Fig. 2 is a transverse section taken along the line 2—2 of Fig. 1;

Fig. 3 is a horizontal longitudinal section taken along the line 3—3 of Fig. 1;

Fig. 4 is a transverse section similar to Fig. 2, showing a modified form of the invention;

Fig. 5 is a view similar to Fig. 1, of another embodiment of my invention;

Figs. 6 and 7 are sections taken on the lines 6—6 and 7—7 of Fig. 5 respectively;

Fig. 8 is an elevation of still another embodiment of my invention;

Figs. 9 and 10 are sections taken along the lines 9—9 and 10—10 respectively, of Fig. 8.

Referring first to Figs. 1 to 3 of the drawings, numeral 2 indicates the arch or truss shoe as a whole, which may be of any preferred or desired transverse cross-sectional contour depending upon the cross-section of the arch segments 8 which the shoe is adapted to support, these segments being preferably

steel rolled sections of any desired cross-section. Numeral 1 indicates a partition wall within the shoe, against which the ends of adjacent segments 8 are adapted to bear and transmit the compression strains directly from one segment to the other. It is preferable that the faces of the partition wall 1 be inclined with respect to one another and form right angles with the side and top walls of the shoe and thereby accommodate segments having squared ends. The angularity between the inclined faces of the partition walls 1 of the shoe 2, it will be apparent, will determine the angularity or curvature of the arch.

The shoe 2, when viewed in transverse section, is of substantially I-shape, the web 2a thereof constituting the side wall of the shoe, and the top and bottom bars 2b and 2c, respectively, of the I constituting the top and bottom walls of the shoe, portions of said walls being in overlapping spaced relation to accommodate and embrace portions of the top and bottom bars of the segment 8 which is in the form of an I-beam. When viewed in horizontal longitudinal section, as shown in Fig. 3, the shoe 2 is of substantially cross (+) shape, the horizontal aligned arms 30 of one bar of the cross corresponding to the side wall or web member of the shoe, and the vertical aligned arms 5 of the other bar of the cross constituting web members adapted to support roof-supporting beams (not shown). At the intersection of the bars of the cross the partition wall 1 provides an offset hub portion with shoulders 9 against which the end faces of the segments 8 bear, for the purpose hereinbefore set forth.

In the modified form of shoe shown in Fig. 4, the bottom wall 4 of the shoe is formed separately from the shoe proper, and may be bolted, riveted, or welded to the segments 8, as shown.

In Figs. 5 to 7 both the top and bottom walls 3 and 4 respectively of the shoe are

separately formed therefrom and secured to the segments 8 by bolting, riveting or welding.

The various modifications of the invention as thus far described, it will be apparent, may be used for either temporary or permanent long span arch constructions, it being obvious that where the constructions are to be temporary, the shoes and segments will be bolted together, whereas where the constructions are to be permanent, the shoes and segments will be riveted or welded together. In the various figures I have accordingly indicated by the numeral 6 crosses whereat the bolts, rivets or welding will be located.

The arch or truss shoe construction, it will be apparent, may be made as castings, drop forgings, pressed steel plates, or built up of assembled elements, an embodiment of the 20 pressed steel plates construction being shown in Figs. 8 to 10. In these figures the shoe 22 is shown as formed from four pressed steel plates which in assembled relation, when viewed in end elevation, constitute two units, 25 each of which has the form of a hollow I, the top and bottom walls of which are provided with a longitudinal rib whereat the outturned edges 23 of the plates of the half I units are brought into abutting relation, and in which, 30 when viewed in front elevation, the abutting top and bottom edges of the units are likewise formed with outturned edges 24 providing a rib. To hold the various elements of the shoe in assembled relation, substantially 35 U-shaped cleats 25 are employed, which are forced over the outwardly turned abutting edges, as best shown in Figs. 8 and 9. The shoe 22 is likewise provided with transversely-extending lateral webs 26 which are 40 adapted to support roof-supporting beams (not shown), these webs 26 being integrally formed with the web members of the shoe, as best shown in Fig. 10. To enable the compression strains to be transmitted from the 45 end face of one of the segments to the end face of another in this type of shoe, a wedge-shaped member 27 is positioned between the adjacent end faces of the half shoe units, as best shown in Figs. 8 and 10, said member 27 50 preferably extending across the full width of the units. It will be obvious that a shoe formed from pressed steel plates may take on other forms, depending upon the cross-section of the steel rolled section segments which it is adapted to cooperate with. It will be 55 equally obvious that, if desired, the cast shoes shown in Figs. 1 to 7 may likewise be formed in halves, or consisting of two units joined together in any appropriate manner.

While I have shown and described several embodiments of my invention, it will be apparent that the constructions disclosed may be varied without departing from the spirit of the invention.

What I claim is:—

1. An arch or truss shoe adapted to support the ends of steel rolled section segments, comprising means against which the end faces of the segments are adapted to bear to permit of the strains being transmitted from the end of one segment to the end of another, said shoe having a contour to engage and hug the various elements of the end portions of the segments, the top and the bottom of said shoe being secured to the complementary faces of the segments for resisting bending strains of the arch.

2. An arch or truss shoe adapted to support the ends of steel rolled section segments, comprising means against which the end faces of the segments are adapted to bear to permit of the strains being transmitted from the end of one segment to the end of another, said shoe having a contour to embrace and hug at least two adjacent elements of the end portions of said rolled section segments, at least one of said elements being secured to the flange of the segments for resisting bending strains of the arch.

3. In a long span arch construction, an arch or truss shoe of substantially cross (+) shape in plan section, the aligned arms of one bar of the cross being adapted to connect the ends of steel rolled section segments to form the arch, and the aligned arms of the other bar of the cross being adapted to support roof-supporting beams.

4. In a long span arch construction, an arch or truss shoe of substantially cross (+) shape in plan section, with an offset hub portion at the intersection of the bars of the cross, the aligned arms of one bar of the cross being adapted to connect the ends of steel rolled section segments to form the arch, the offset hub portion forming abutments against which the end faces of said segments are adapted to bear to permit the compression strains being transmitted from the end face of one segment to the end face of another segment, and the aligned arms of the other bar of the cross being adapted to support roof-supporting beams.

5. In a long span arch construction, an arch or truss shoe of substantially cross (+) shape in plan section, with an offset portion at the intersection of the bars of the cross, said offset portion when viewed in longitudinal vertical section presenting an abutment inclined to the longitudinal axis of the shoe.

6. In a long span arch construction, an arch or truss shoe of substantially (+) shape in plan section, the aligned arms of one bar of the cross being adapted to connect the ends of steel rolled section segments to form the arch, and the aligned arms of the other bar of the cross being adapted to support roof-supporting means, said shoe hav-

ing means at the top and bottom for resisting bending strains of the arch.

7. In a long span arch construction, an arch or truss shoe of substantially (+) shape in plan section, with an offset portion 5 at the intersection of the bars of the cross, said offset portion when viewed in longitudinal vertical section presenting an abutment inclined to the longitudinal axis of the shoe, 10 said shoe having means at the top and bottom for resisting bending strains of the arch.

In witness whereof, I have hereunto signed my name.

LOUIS DAVIDSON.
